UNITED STATES PATENT OFFICE.

WILLIAM L. HAMILTON, OF CHICAGO, ILLINOIS.

REGISTER-HOOK.

No. 874,500.

Specification of Letters Patent.

Patented Dec. 24, 1907.

Application filed April 29, 1907. Serial No. 371,001.

To all whom it may concern:

Be it known that I, WILLIAM L. HAMILTON, a citizen of the United States, residing in the city of Chicago, county of Cook, and State of Illinois, have invented a new and useful Improvement in Register-Hooks Used by Printers to Adjust and Hold Printing-Plates in a Form Made Up for Printing Purposes.

The object of my invention is to simplify the construction, provide for quicker and easier adjustment, better holding power, and greater strength and for a narrower margin between printing plates.

The manner in which I accomplish my object is described in the following specification and illustrated in the accompanying drawings in which:

Figure 1 is a front end elevation. Fig. 2 is a side elevation. Fig. 3 a longitudinal vertical central section on the line 2—2 Fig. 1. Fig. 4 is a top plan view. Fig. 5 is a cross section on the line 5—5 Fig. 3 and Fig. 6 is a longitudinal view of the threaded shaft.

In the drawings A indicates the main body which is rectangular in form. Extending longitudinally into this body to the wall A¹ is a cylindrical bore B the diameter of which intersects the top line of the main body. In the top of the body A are opposite parallel guideways C. These guideways extend the full length of the body. The base line of these guideways C¹ and the top line of the wall A¹ correspond. Inserted in and fitting the bore B is a parallel screw D, this screw is threaded its entire length. One end D¹ of this screw is faced to butt up against the wall A¹ and the other end D² is faced off flush with the front end of the body A. In the end D² of this screw are a series of radial channels D³. Adjacent to the end D¹, in the surface of the screw, is an annular channel D⁴ and between this annular channel and the end D² are a series of radial holes D⁵. These holes may be arranged in parallel lines corresponding with the number and position of the end channels D³ or they may be staggered. The channels D³ are adapted in size and shape to receive the angular end of a lever bar, and the holes D⁵ are adapted in size to receive the cylindrical end of the same lever bar. Extending transversely through the main body are holes E and inserted therein is a rod E¹.

The location and size of these holes and rod corresponds with that of the annular channel D⁴ in the screw and is adapted to hold said screw in the bore B and against the wall A¹. Slidably supported in the guideways C is a clutch F. This clutch has an arched under surface F¹. This surface is threaded and thereby adapted to mesh with the threaded surface of the screw D. The sides F² of the clutch are nearly flush with the sides of the body A. At one end of this clutch are transverse double jaws F³ which project above the top F⁴ of the clutch. The inside faces F⁵ of each of these jaws forms an acute angle with the top of the clutch F⁴. Between the jaws the front of the clutch is recessed F⁶ to a depth corresponding with the depth of the radial channels D³ in the end of the screw, this recess permits the insertion of a lever into said radial channels when the jaw end of the clutch is flush with the front end of the body A.

When my register hook is constructed as described and illustrated it is put together and operated as follows. The screw D is inserted in the bore B and the rod E¹ is inserted in the holes E and thereby engages the screw in the channel D⁴. This pin the ends of which are made flush with the sides of the body A resists the side pressure and thereby tends to prevent the jamming of the clutch in the guideways; it also prevents the end D¹ of the screw from being raised by pressure on the jaws F³ and any lateral movement of the screw which is free to be rotated in the bore B. The clutch F can be inserted at either end of the guideways and be moved into position therein by the rotation of the screw. The rotation of the screw is effected by the insertion of the lever G either in the channels D³ or holes D⁵. The operation of the screw by the insertion of the lever in the holes is necessary when the jaw end of the clutch projects over the channels D³ and may be used when the clutch is required at the other end of the body A. By this construction I obtain the fullest limit of movement of the clutch, and easy and powerful adjustment in any position. The double jaws also cover the longest transverse engagement with the plates they are adapted to secure.

It is obvious that the holes E and the rod E¹ may be threaded at either end, and as a screw, be an equivalent for the rod shown, hence I reserve the right to the use of a screw 5 in place of the rod.

What I desire to secure by Letters Patent is:

1. A device of the kind described consisting of the main body having a bore, guideways, end wall, and transverse holes; the screw rotatably supported in said bore, said screw having radial end channels, a series of radial holes and an annular channel; the rod insertible in said transverse holes adapted 10 to extend through said annular channel and hold said screw in said bore; the clutch slidably supported in said guideways in said body, said clutch having an arched threaded under surface adapted to mesh into said 15 screw and said clutch being thereby adapted to be moved in said guideways by the rotation of said screw.

2. In a device of the kind described, the combination with the main body, said body 25 having a longitudinal bore therein, adapted to admit a screw, longitudinal guideways adapted to support a clutch, and holes adapted to support a rod extending transversely through said body and bore therein; of a 30 screw adapted to fit said bore in said body, said screw having a plurality of radial channels in the front end and an annular channel in the threaded surface adapted to admit part of said rod and to be thereby retained in 35 said bore in said body; and a clutch adapted to fit and slide in said guideways and to be engaged by said screw and to be moved in said guideways by the rotation of said screw.

3. In a device of the kind described, the 40 combination with the main body having a longitudinal bore and guideways, and a rod insertible transversely through said body and bore therein; of a screw rotatably supported in said bore, said screw having a plurality of radial channels in the front end, an 45 annular channel adapted to admit said rod and a series of radial holes in the surface of said screw between said front end and said channel; and a clutch slidably supported in 50 said guideways in contact with the surface

of said screw and adapted to be moved by the rotation of said screw in said body.

4. In a device of the kind described, the combination with the main body having a longitudinal bore and guideways, and a screw 55 rotatably supported in said bore, said screw having a plurality of radial channels in the front end, a series of radial holes and an annular channel in the threaded surface; of means insertible transversely in said body 60 adapted to enter said annular channel and to thereby retain said screw in rotatable position in said bore; and a clutch slidably supported in said guideways in contact with part of the threaded surface of said screw 65 and thereby adapted to be moved in said guideways by the rotation of said screw.

5. In a device of the kind described, the combination with the main body, the screw rotatably supported therein, said screw having an annular channel, and means insertible in said body and said channel adapted to hold said screw in said body; of a clutch 70 slidably supported in guideways in said body, said clutch having an arched threaded under 75 surface adapted to engage the threaded surface of said screw, said clutch being moved in said guideways by the rotation of said screw in said body in contact with the arched under surface of said clutch.

6. In a device of the kind described, the combination with the main body having a longitudinal bore and guideways, the screw rotatably supported in said bore, said screw having radial end channels and radial holes 85 and an annular channel in its threaded surface, the means insertible transversely through said body and in said annular channel in said screw; of a clutch slidably supported in the guideways in said body, said 90 clutch having a pair of jaws and an arched threaded under surface in contact with the threaded surface of said screw and thereby adapted to be moved in said body by the rotation of said screw.

WILLIAM L. HAMILTON.
